(57) **CLAIM**

The ornamental design for an element for adhesive thermometer, as shown and described.

DESCRIPTION

FIG. 1 is a perspective view of an element for an adhesive thermometer showing our new design;
FIG. 2 is a front view thereof;
FIG. 3 is a rear view thereof;
FIG. 4 is a left view thereof;
FIG. 5 is a right view thereof;
FIG. 6 is a top view thereof;
FIG. 7 is a bottom view thereof; and,
FIG. 8 is another perspective view thereof showing the element in an environment in which it may be used.
The broken lines are provided for environmental purposes only and form no part of the claimed design.
